BOBBIN WINDING MECHANISM

Waldemar A. Ayres, Lakewood, Ohio, assignor to White Sewing Machine Corporation, Lakewood, Ohio, a corporation of Delaware

Application January 25, 1955, Serial No. 483,908

19 Claims. (Cl. 242—22)

The present invention relates to a sewing machine and more particularly to a novel and improved bobbin winder mechanism for such a machine.

An object of the present invention is the provision of a new and improved bobbin winding device for a sewing machine which device will perform its bobbin winding operation while the rest of the machine is in use and which device will automatically stop rotation of the bobbin when a predetermined amount of thread has been wound upon the bobbin.

Another object of the invention is the provision of a new and improved bobbin winding device of the above described type which device includes readily adjustable means for preselecting the amount of thread that is to be wound upon a particular bobbin, and after which amount of material has been wound upon the bobbin, the device automatically stops further rotation of the bobbin.

A further object of the invention is the provision of a new and improved bobbin winding device of the above described type which is simple and rugged in design, efficient in its operation, and which is inexpensive to manufacture.

A more specific object of the invention is the provision of a new and improved bobbin winding device comprising a rotatable shaft adapted to receive a bobbin, which bobbin is driven by the shaft when in one position on the shaft and which is not driven by the shaft when moved axially to another position on the shaft, a thread feeler arm adapted to extend between the flanges of the bobbin and move it axially between its two positions, said feeler arm being journaled about an axis generally parallel to said shaft for both rotational movement about and axially movable along said axis, spring means biasing said feeler arm toward said shaft and toward said other position of said bobbin wherein it is not rotated by said shaft, and means preventing movement of said feeler arm toward said other position of said bobbin wherein it is not rotated by said shaft until the feeler arm is rotated a predetermined distance away from said shaft by thread wound upon the bobbin, at which time said spring means moves said feeler arm and the bobbin engaged thereby into its other position wherein it is not rotated.

A still more specific object of the invention is the provision of a new and improved bobbin winding device of the above described type which utilizes a frictional driving connection between the shaft and the bobbin to drive the bobbin and which moves the bobbin axially of the shaft into engagement with a braking device to stop rotation of the bobbin after a predetermined amount of material is wound upon the bobbin, and which holds it in this position to prevent further rotation of the bobbin.

The invention resides in certain constructions and combinations and arrangements of parts and further objects and advantages will be apparent to those skilled in the art to which the invention relates from the following description of two preferred embodiments of the invention described with reference to the accompanying draw-

2

ings forming a part of this specification in which similar reference characters designate corresponding parts and in which,

Fig. 1 is a fragmentary plan view of the head of a sewing machine showing one form of bobbin winding device embodying the principles of the present invention;

Fig. 2 is a fragmentary cross sectional view taken approximately on the line 2—2 of Fig. 1;

Fig. 3 is a cross sectional view taken approximately on line 3—3 of Fig. 1;

Fig. 4 is a fragmentary sectional view taken approximately on the line 4—4 of Fig. 3;

Fig. 5 is a fragmentary sectional view taken approximately on the line 5—5 of Fig. 3;

Fig. 6 is a fragmentary sectional view taken approximately on the line 6—6 of Fig. 3;

Fig. 7 is a fragmentary sectional view taken approximately on the line 7—7 of Fig. 2; and

Fig. 8 is a fragmentary cross sectional view of the head of a sewing machine showing a second form of bobbin winding device embodying the principles of the present invention.

The embodiment of the invention shown in Figs. 1 through 7 of the drawing generally comprises bobbin supporting and driving means, indicated generally at A, adapted to support and drive a bobbin B when it is in one position on a rotating shaft, and to support but not drive the bobbin when the bobbin is slid axially to a second position on the shaft; thread sensing means generally indicated at C adapted to move the bobbin into its second position when a predetermined amount of thread is wound upon the bobbin; and adjustable abutment means, generally indicated at D for preselecting the amount of material which when wound upon the bobbin will cause the thread sensing means C to move the bobbin into its second position.

The bobbin supporting and driving means A shown in the drawing comprises a vertically extending shaft 10 journaled in the horizontal arm or bracket 11 (only a portion of the top member of which is shown) of the head of a sewing machine and a portion of which shaft 10 projects upwardly from the top surface of the bracket 11. The shaft 10 is rotated or driven by an electric motor, not shown, as well understood in the art, and a belt pulley 12 is attached to the projecting end of the shaft 10 immediately above the head bracket 11 as by a pin 13 for driving other portions of the sewing machine mounted in the head and forming no part of the present invention. The bobbin supporting and driving means A shown in the drawing utilizes a frictional type of bobbin drive, as will later be described, and employs a friction braking device 14 for stopping rotation of the bobbin B when it is moved to its second position wherein the bobbin is not rotated by the shaft. The frictional braking device shown at 14, comprises an annular disk-shaped portion 15, positioned immediately above the pulley 12 and attached to the horizontal arm 11 of the sewing machine as by a depending bracket 16 and machine screw 17. The upper surface of the disk-shaped portion 15 of the braking device 14 is provided with an annular ring 18 made of rubber or other suitable friction material adapted to engage the lower flange of a bobbin B mounted on the shaft 10 and stop its rotation when it is moved to its lower or second position in engagement therewith.

Alternatively, other forms of braking devices may be used, as, for example, a positive type of braking device wherein the braking device 14 would be provided with an upwardly extending pin adapted to engage a hole or other form of abutment surface on the lower flange of the bobbin B.

The end portion of the shaft 10 which projects upwardly from the braking device 15 is of reduced diameter

to receive the cylindrical shaft receiving opening of a bobbin, and the shaft is provided with a frictional type of driving element as mentioned above. The portion of the shaft 10 above the pulley 12 is provided with a longitudinally extending groove 20 in which is positioned a longitudinally extending lever-like friction or pressure element 21 fastened at its lower end to the shaft 10 by a pin 22 and which is adapted to be forced outwardly by a spring blade 23 positioned between the bottom of the groove 20 and the pressure element 21. The spring blade 23 is designed to provide sufficient pressure between the element 21 and the cylindrical surface of the shaft receiving hole of the bobbin B to rotate the bobbin against the counter-torque created by the pull of the thread being wound upon the bobbin and the spring 23 is held in place by means of a hooked end which fits around the pinned end of the pressure element 21.

The thread sensing means C shown in the drawing is adapted to hold a bobbin B positioned on the shaft 10 in its upper operative or winding position until a predetermined amount of thread is wound upon the bobbin and to thereafter move and hold the bobbin in its non-operative or non-winding position. The thread sensing means C shown comprises a generally cylindrically shaped structure or element 30 having a generally flat rectangularly shaped feeler arm 31 projecting outwardly from its external surface with the width of the blade extending longitudinally of the cylindrically shaped structure. The cylindrically shaped structure 30 has an axially extending hole or bore 32, the upper end of which is counter-bored as at 33, and the structure is attached to the horizontal bracket 11 of the sewing machine about a vertical axis generally parallel to that of the shaft 10 by means of a headed pin 34 whose head 35 is positioned in the counterbore 33 and whose lower end is threaded into the top of the horizontal bracket 11 of the machine.

The thread sensing element or structure 30 is held in its upper or bobbin winding position by means of an abutment arm 36 projecting outwardly from its cylindrical surface and which bears against the abutment surface of the adjustable abutment means D as will later be explained. The thread sensing element 30 is biased downwardly in the axial direction of the braking device 15 and the abutment arm 36 is held in engagement with the abutment surface of the adjustable abutment means D by means of a coil spring 37 the lower end of which bears against the bottom wall 38 of the counterbore 33 and the upper end of which bears against the head 35 of the pin 34. The feeler arm 31 of the thread sensing element 30 is also biased toward the shaft 10 by means of a coil spring 39 positioned about a pilot or boss 40 on the lower end of the thread sensing element 30. One end of the spring 39 is positioned in a hole 41 in the bottom of the thread sensing element 30 and the other end of the spring 39 is positioned in a hole 42 in an annularly shaped abutment member 43 adjustably fastened to the lower end of the pin 34 just above the arm 11 as by a setscrew 44.

The feeler arm 31 is adapted to extend between the flanges of a bobbin B mounted on the shaft 10 to move the bobbin from its winding position, shown in Fig. 2, into engagement with the braking device 15 when a predetermined amount of thread has been wound upon the bobbin, as will later be explained. To insure that the bobbin will be moved into engagement with the braking device 15 even though the bobbin has been wound full of thread and the feeler arm 31 is moved out of engagement with the bobbin's flanges, an L-shaped arm or clip 45 is formed on the top edge of the feeler arm 31 with its horizontal portion being adapted to extend inwardly over the top of the bobbin.

The adjustable abutment means D shown, comprises a horizontal disk-shaped abutment or stop member 50 positioned beneath the abutment arm 36 of the thread sensing element 30 and having an annularly shaped segmental boss 51 extending around 180 degrees of its upper

surface and against which the abutment arm 36 is adapted to bear. The disk-shaped abutment or stop member 50 is rotatably mounted on the horizontal arm of the sewing machine by a vertically extending shaft or pin 52 which extends through an axially extending hole 53 in the member 50 and which is journaled in the horizontal arm 11. The abutment member is rigidly fixed to the shaft 52 by a pin 54 and the upper end of the shaft is provided with a knurled knob 55 such that the location of the annular boss 51 might be changed relative to the abutment arm 36. A flat sheet metal pointer 56 is adjustably attached to a slightly enlarged portion 57 of the shaft 52 by means of an annular portion which is split radially on its side opposite its pointer arm and is pressed over the enlarged portion 57. The lower end of the shaft 52 which projects beneath the member 11 is threaded and is of slightly reduced diameter to provide a shoulder 58 against which a stop plate 59 is locked by a nut 60 and a concave annular disk-shaped spring 61 is positioned on the shaft 52 between the stop-plate 59 and the bottom of the top member of the horizontal arm 11 to hold the abutment member in its set position. The abutment member 50 is prevented from being moved beyond predetermined limits by means of a stop pin 62 positioned in an arcuate groove or notch in the stop plate 59, and threaded into the bottom of the member 11. The sewing machine shown is provided with a sheet metal cover 63 which extends above and covers the pulley and drive belt mechanisms of the head of the machine and which is provided with a scale 30 against which the pointer 56 may be read.

To operate the bobbin winding device just described, the knob 55 of the adjustable abutment means D is turned to a setting corresponding to the amount of thread desired to be wound upon the bobbin; the feeler arm 31 of the thread sensing element 30 is rotated clockwise, as viewed in Fig. 1, away from the shaft 10; a bobbin B to which one end of the thread to be wound upon the bobbin is tied is slipped upon the shaft 10; the thread sensing element 30 is lifted upwardly until its abutment arm 36 is above the boss 51; and the thread sensing element 30 is turned counterclockwise as viewed in Fig. 1 while still holding the element 30 upwardly meanwhile positioning the bobbin on the shaft 10 such that the feeler arm 31 moves between the flanges of the bobbin B. The thread sensing element is then freed, whereupon spring 40 forces the feeler arm 31 against the bottom of the thread receiving portion of the bobbin and the spring 37 forces the abutment arm 36 against the top surface of the boss 51. The operator is thereafter free to go about his sewing operation. As the machine is used, rotation of the shaft 10 winds the thread upon the bobbin B and when an amount has been wound upon the bobbin corresponding to the setting of the abutment means D, the thread sensing element 30 will have been rotated by its feeler arm 31 until its abutment arm 36 just clears the edge of the boss 51 whereupon force from the spring 37 moves the thread sensing element 30 downwardly moving its feeler arm and the bobbin engaged thereby downwardly into engagement with the braking device 14, stopping rotation of the bobbin. The operator may continue to perform his sewing operation with which he is occupied during which time the pressure element 21 slips around the inside cylindrical surface of the bobbin shaft receiving hole. When the operator desires to use the bobbin, the feeler arm 31 is rocked away from the bobbin and the bobbin is slipped upwardly off of the shaft. When the thread sensing element is now released the feeler arm is moved back to the position where the winding operation stopped and is held in this position away from the shaft 10 by engagement 70 of the abutment arm 36 against the edge of the boss 51.

A second embodiment of the invention is shown in Fig. 8 of the drawing and in which the shaft 10, its bobbin driving element, and the bobbin braking device 14 are identical with those of the previous embodiment and are 75 so numbered in the drawing. The thread sensing element

70 of the present embodiment is a cylindrical structure very similar to that of the previous embodiment and has a feeler arm 71 shaped identically to that of the previous embodiment. The thread sensing element 70 is drilled longitudinally and fixed to the upper end of a vertically extending shaft 72 inserted therethrough by a setscrew 73 and the shaft 72 is journaled in the horizontal arm 11 of the machine in a generally parallel relationship to shaft 10. The bottom surface 74 of the thread sensing element 70 is provided with an axially extending projection or abutment 75 adapted to engage the top end surface of a cylindrical abutment or stop member 76 journaled about the shaft 72 beneath the thread sensing element 70 and the top surface of the horizontal arm 11 of the sewing machine. The lower end of the abutment member 76 is provided with an enlarged portion or flange 77 and the abutment member 76 is held against the arm 11 by a forked pressure spring or clip 78 the forked portion of which is slipped around the cylindrical abutment member 76 over the flange 77 in a manner permitting rotation of the abutment member 76 and the other end of the clip being fastened to the arm 11 as by a machine screw 80. The upper surface of the abutment member 76 is provided with a segmental boss 81 extending around approximately 180° of its upper surface and against which the projection 75 of the thread sensing element 70 is adapted to bear. The thread sensing element 70 is biased toward the abutment member 76 by a combination torsion and compression coil spring 82 positioned about the shaft 72 beneath the top of the arm 11. One end of the spring 82 is positioned in a hole 83 in the arm 11 and the other end of which is positioned in a hole 84 in the bottom of a cup shaped spring abutment member 85 which surrounds the spring and which is fastened to the lower end of the shaft 72 by a setscrew 86. An upwardly extending arm or member 87 having a pointer 88 on its upper end is provided on the abutment member 76 to permit adjustment of the position of the segmental boss 81 and thus the amount of thread to be wound upon a bobbin and a scale 90 is provided on the sheet metal cover 63 beneath the pointer 88 to provide a visual indication of the setting of the abutment member. The operation of the present embodiment and manner in which a bobbin is installed thereon is similar to that of the previous embodiment and will not further be described.

While the preferred embodiments of the invention have been shown and described as using a frictional type of driving engagement between the bobbin driving shaft and the bobbin, it is not limited thereto and other types of driving connections may be employed. Where, for example, a positive type of drive is to be used, the bobbin may be provided with a keyway, the upper end of which is adapted to engage a short section of key positioned on the upper end of the shaft when the bobbin is in its upper driving position and which keyway of the bobbin will be moved out of engagement with the key when the bobbin is moved to its lower or non-driven position. Alternatively any other suitable type of frictional driving connection or positive driving connection can be utilized.

It is further to be understood that while the preferred embodiments of the invention have been described as having the first or bobbin driving position adjacent the end of the shaft, and the second or non-driving position spaced farther in on the shaft, that it is not so limited and that where suitable modifications are made, the positions may be reversed. Were this to be done a further type of driving connection could be utilized in which a flange would be provided adjacent the lower end of the bobbin receiving portion and an upwardly extending drive pin provided on its upper surface for engaging a hole or abutment on the lower flange of the bobbin. With this arrangement the thread sensing element and abutment member would be rearranged to move the bobbin upwardly when the predetermined amount of thread is wound upon the bobbin and the flange of the bobbin thereby removed

from engagement with the drive pin. A movable type of braking element adapted to be swung in and out of position to permit installation and removal of a bobbin upon the shaft may be provided to engage the top flange of the bobbin and stop its rotation when the bobbin is moved to its upper position. In those instances where the bobbin is freely journaled upon the shaft when the bobbin is moved to its non-driven position, the braking element may not be required to stop rotation of the bobbin.

While the preferred embodiments of the invention have been described in considerable detail I do not wish to be limited to the particular constructions shown which may be varied within the scope of the invention, and it is the intention to cover hereby all adaptations, modifications and arrangements thereof which come within the practice of those skilled in the art to which the invention relates and within the scope of the appended claims.

Having thus described my invention, I claim:

1. A bobbin winder for a sewing machine comprising, 20 a stationary support member, a first shaft rotatably mounted in said stationary support member, said shaft being adapted to receive a bobbin in a first position wherein the bobbin is rotated by said shaft and in a second position spaced axially from said first position and wherein the bobbin is not rotated by said shaft, a second shaft supported by said stationary support member in a position generally parallel to said first shaft, a thread sensing element rotatably mounted on said second shaft and adapted for movement axially of said second shaft, said 25 element having a feeler arm adapted to extend between the flanges of a bobbin mounted on said first shaft and having an abutment surface which projects in the axial direction that said second bobbin position is spaced from said first bobbin position, spring means biasing said feeler 30 arm of said thread sensing element towards said first shaft and axially of said shafts in the direction that said second bobbin position is spaced from said first bobbin position, an adjustable stop member supported by said stationary support member and having an abutment surface against which the abutment surface of said thread sensing element is adapted to bear, said abutment surfaces being shaped to permit said spring means to move said thread sensing element axially to a position wherein a bobbin engaged by its feeler arm will be moved to its 35 second position when the feeler arm is rotated away from said first shaft a predetermined distance.

2. A bobbin winder for a sewing machine comprising, 40 a stationary support member, a first shaft rotatably mounted in said stationary support member, said shaft being adapted to receive a bobbin in a first position wherein the bobbin is rotated by said shaft and in a second position spaced axially from said first position and wherein the bobbin is not rotated by said shaft, a second shaft supported by said stationary support member in a position generally parallel to said first shaft, a thread sensing element rotatably mounted on said second shaft and adapted for movement axially of said second shaft, said element having a feeler arm adapted to extend between the flanges of a bobbin mounted on said 45 first shaft and having an abutment surface which projects in the axial direction that said second bobbin position is spaced from said first bobbin position, spring means biasing said feeler arm of said thread sensing element towards said first shaft and axially of said shafts in the direction that said second bobbin position is spaced from said first bobbin position, an adjustable stop member supported by said stationary support member and having a stepped abutment surface against which the abutment surface of said thread sensing element is adapted to bear, said stepped abutment surface being shaped to permit said spring means to move said thread sensing element axially to a position wherein a bobbin engaged by its feeler arm will be moved abruptly to its second position when the feeler arm is rotated away from said 55 first shaft a predetermined distance.

3. A bobbin winder for a sewing machine comprising, a stationary support member, a first shaft rotatably journaled in said stationary support member, said shaft being adapted to receive a bobbin in a first position wherein the bobbin is rotated by said shaft and in a second position spaced axially from said first position and wherein the bobbin is not rotated by said shaft, a second shaft supported by said stationary support member in a position generally parallel to said first shaft, a thread sensing element rotatably mounted on said second shaft and adapted for movement axially of said second shaft, said element having a feeler arm adapted to extend between the flanges of a bobbin mounted on said first shaft, a stop member positioned adjacent said second shaft and rotatably mounted on said stationary support member about an axis generally parallel to said first and second shafts, said stop member having a stepped abutment surface on its end surface facing in the axial direction of said first bobbin position, an abutment arm on said thread sensing element adapted to engage the stepped abutment surface of said stop member, and spring means biasing said feeler arm of said thread sensing element toward said first shaft and biasing said thread sensing element in a direction axially of said shafts toward said second bobbin position wherein a bobbin mounted on said first shaft will not be rotated, said abutment surface of said stop member being adapted to position a bobbin engaged by said feeler arm of said thread sensing element in its first position when the feeler arm is adjacent said first shaft and to permit said feeler arm to move the bobbin into its second position when said feeler arm is rotated away from said first shaft.

4. A bobbin winder for a sewing machine comprising, a stationary support member, a first shaft rotatably journaled in said stationary support member, said shaft being adapted to receive a bobbin in a first position wherein the bobbin is rotated by said shaft and in a second position spaced axially from said first position and wherein the bobbin is not rotated by said shaft, a second shaft journaled in said stationary support member, a thread sensing element fixed to said second shaft, an annular stop member rotatably mounted on said second shaft and spaced axially from said thread sensing element in the direction that said second bobbin position is spaced from said first bobbin position, spring means operatively connected between said stationary support member and said second shaft for rotating the feeler arm of said thread sensing element fixed thereto toward said first shaft and for moving said second shaft in the axial direction of said second bobbin position, said stop member and said thread sensing element having cooperating stepped abutment surfaces on their adjoining faces adapted to hold said members in their most spaced apart positions with the feeler arm of the thread sensing element holding a bobbin engaged thereby in its bobbin driving position when said feeler arm is adjacent said first shaft and to permit said feeler arm to move the bobbin to its second position when said feeler arm is rotated away from said first shaft.

5. A bobbin winder for a sewing machine comprising, a stationary support member, a shaft rotatably journaled in said stationary support member, said shaft having a bobbin receiving portion on which a bobbin may be slid axially, means providing frictional driving engagement between said shaft and a bobbin positioned on the bobbin receiving portion thereof, a brake member positioned adjacent one end of said bobbin receiving portion of said shaft and attached to said support member for stopping rotation of the bobbin when it is moved axially thereagainst, a thread feeler arm adapted to extend between the flanges of a bobbin positioned on the bobbin receiving portion of said shaft and attached to said support member about an axis generally parallel to said rotatable shaft in a manner permitting both rotation about and movement axially of said axis, spring

means biasing said feeler arm toward said shaft and toward said brake member, and means preventing movement of said feeler arm toward said brake member when said feeler arm is within a predetermined distance of engagement with said shaft.

6. A bobbin winder for a sewing machine comprising, a stationary support member, a shaft rotatably journaled in said stationary support member, said shaft having a bobbin receiving portion on which a bobbin may be slid axially, means providing frictional driving engagement between said shaft and a bobbin positioned on the bobbin receiving portion thereof, a brake member positioned adjacent one end of said bobbin receiving portion of said shaft and attached to said support member for stopping rotation of the bobbin when it is moved axially thereagainst, a second shaft supported by said stationary support member in a position generally parallel to said first shaft, a thread sensing element rotatably mounted on said second shaft and adapted for movement axially of said second shaft, said element having a feeler arm adapted to extend between the flanges of a bobbin mounted on said first shaft, a stop member positioned adjacent said second shaft and rotatably mounted on said stationary support member about an axis generally parallel to said first and second shafts, said stop member having a stepped abutment surface on its side facing in the axial direction in which the bobbin receiving portion of said first shaft is positioned relative to said brake member, an abutment arm on said thread sensing element adapted to engage the stepped abutment surface of said stop member, and spring means biasing said feeler arm of said thread sensing element toward said first shaft and biasing said thread sensing element axially in a direction toward said stop member, said abutment surface of said stop member being adapted to position a bobbin engaged by said feeler arm of said thread sensing element away from said brake member when said feeler arm is adjacent said first shaft and to permit said feeler arm to move the bobbin against said brake member when the feeler arm is moved away from said first shaft a predetermined distance.

7. A bobbin winder for a sewing machine comprising, a stationary support member, a shaft rotatably journaled in said stationary support member, said shaft having a bobbin receiving portion on which a bobbin may be slid axially, means providing frictional driving engagement between said shaft and a bobbin positioned on the bobbin receiving portion thereof, a brake member positioned adjacent one end of said bobbin receiving portion of said shaft and attached to said frame for stopping rotation of the bobbin when it is moved axially thereagainst, a second shaft journaled in said stationary support member, a thread sensing element fixed to said second shaft, an annular stop member rotatably mounted on said second shaft axially in the direction in which the brake member is positioned relative to the bobbin receiving portion of said first shaft, spring means operatively connected between said stationary support member and said second shaft for rotating the feeler arm of said thread sensing element fixed thereto toward said first shaft and for forcing said thread sensing element against said stop member, said stop member and said thread sensing element having cooperating step abutment surfaces on their abutting surfaces adapted to hold said members in their most spaced apart positions with the feeler arm of the thread sensing element holding a bobbin engaged thereby away from said brake member when said feeler arm is adjacent said first shaft and to permit said feeler arm to move the bobbin against said brake member when said feeler arm is rotated away from said first shaft a predetermined distance.

8. A bobbin winder for a sewing machine comprising, a stationary support member, a shaft rotatably journaled in said stationary support member, said shaft hav-

ing a bobbin receiving portion on which the bobbin may be slid axially, said shaft having an axially extending groove in its bobbin receiving portion, a friction member in said groove, a spring in said groove beneath said friction member and adapted to force said friction member radially outwardly of said groove against a bobbin positioned on said shaft, a brake member positioned adjacent one end of said bobbin receiving portion of said shaft and attached to said support member for stopping rotation of the bobbin when it is moved axially thereagainst, a thread feeler arm adapted to extend between the flanges of a bobbin positioned on said shaft and attached to said support member about an axis generally parallel to said rotatable shaft in a manner permitting both rotation about and movement axially of said axis, spring means biasing said feeler arm toward said shaft and toward said brake member, and means preventing movement of said feeler arm toward said brake member when said feeler arm is within a predetermined distance of engagement with said shaft.

9. A bobbin winder for a sewing machine comprising, a stationary support member, a shaft rotatably journaled in said stationary support member, said shaft having a bobbin receiving portion on which the bobbin may be slid axially, said shaft having an axially extending groove in its bobbin receiving portion, a friction member in said groove, a spring in said groove beneath said friction member and adapted to force said friction member radially outwardly of said groove, a brake member positioned adjacent one end of said bobbin receiving portion of said shaft and attached to said support member for stopping rotation of the bobbin when it is moved axially thereagainst, a second shaft supported by said stationary support member in a position generally parallel to said first shaft, a thread sensing element rotatably mounted on said second shaft and adapted for movement axially of said second shaft, said element having a feeler arm adapted to extend between the flanges of a bobbin mounted on said first shaft, a stop member positioned adjacent said second shaft and rotatably mounted to said stationary support member about an axis generally parallel to said first and second shafts, said stop member having a stepped abutment surface on its side facing in the axial direction in which the bobbin receiving portion of said first shaft is positioned relative to said brake member, an abutment arm on said thread sensing element adapted to engage the stepped abutment surface of said stop member, and spring means biasing said feeler arm of said thread sensing element toward said first shaft and biasing said thread sensing element axially in a direction towards said stop member, said abutment surface of said stop member being adapted to position a bobbin engaged by said feeler arm on said bobbin receiving portion of said first shaft away from said brake member when said feeler arm is adjacent said first shaft and to permit said feeler arm to move the bobbin against said brake member when the feeler arm is moved away from said first shaft a predetermined distance.

10. A bobbin winder for a sewing machine comprising, a stationary support member, a shaft rotatably journaled in said stationary support member, said shaft having a bobbin receiving portion on which the bobbin may be slid axially, said shaft having an axially extending groove in its bobbin receiving portion, a friction member in said groove, a spring in said groove beneath said friction member and adapted to force said friction member radially outwardly of said groove, a brake member positioned adjacent one end of said bobbin receiving portion of said shaft and attached to said support member for stopping rotation of the bobbin when it is moved axially thereagainst, a second shaft journaled in said stationary support member, a thread sensing element fixed to said second shaft, an annular stop member rotatably mounted on said second shaft spaced from said

thread sensing element in the axial direction in which the brake member is positioned relative to the bobbin receiving portion of said first shaft, spring means operatively connected between said stationary support member and said second shaft for rotating the feeler arm of said thread sensing element fixed thereto toward said first shaft and for moving said thread sensing element against said stop member, said stop member and said thread sensing element having cooperating stepped abutment surfaces on their abutting faces adapted to hold said members in their most spaced apart positions with the feeler arm of the thread sensing element holding a bobbin engaged thereby away from said brake member when said feeler arm is adjacent said first shaft and to permit said feeler arm to move the bobbin against said brake member when said feeler arm is rotated away from said first shaft a predetermined distance.

11. A bobbin winder for a sewing machine comprising, a stationary support member, a shaft rotatably journaled in said stationary support member and having a cantilevered bobbin receiving portion projecting outwardly from said support member and on which the bobbin may be slid axially, said projecting portion of said shaft having an axially extending groove therein, a friction member in said groove, a spring in said groove beneath said friction member and adapted to force said friction member radially outwardly of said groove against a bobbin positioned on said cantilevered portion of said shaft, a friction brake member positioned about said shaft adjacent said support member and affixed thereto, a thread feeler arm adapted to extend between the flanges of a bobbin positioned on said cantilevered portion of said shaft above said friction brake member, said feeler arm being attached to said support member about an axis generally parallel to said shaft in a manner permitting both rotation about and movement axially of said axis, spring means biasing said feeler arm toward said shaft and toward said friction brake member, and means preventing movement of said feeler arm toward said brake member when said feeler arm is within a predetermined distance of engagement with said shaft.

12. A bobbin winder for a sewing machine comprising, a stationary support member, a shaft rotatably journaled in said stationary support member and having a cantilevered bobbin receiving portion projecting outwardly from said support member and on which the bobbin may be slid axially, said projecting portion of said shaft having an axially extending groove therein, a friction member in said groove, a spring in said groove beneath said friction member and adapted to force said friction member radially outwardly of said groove against a bobbin positioned on said cantilevered portion of said shaft, a friction brake member positioned about said shaft adjacent said support member and affixed thereto, a pin stationary supported by said stationary support member in a position generally parallel to said shaft, an abutment member adjustably clamped to said pin adjacent said support member, a thread sensing element rotatably mounted on said pin above said abutment member and adapted for movement axially of said pin, said element having a feeler arm adapted to extend between the flanges of a bobbin mounted on said bobbin receiving portion of said shaft, spring means operatively connected between said thread sensing element and said abutment member biasing said feeler arm of said thread sensing element toward said shaft, spring means biasing said thread sensing element in a direction axially of said pin toward said abutment member, a disk-shaped stop member positioned adjacent said pin and rotatably mounted to said stationary support member about an axis generally parallel to said pin, said stop member having a stepped abutment surface on its upper end, and an abutment arm on said thread sensing element adapted to engage the stepped abutment surface of said stop member, said abutment surface of said stop member being stepped downwardly

in a direction to which said abutment arm is rotated when said feeler arm of said thread sensing element is rotated away from said shaft.

13. A bobbin winder for a sewing machine comprising, a stationary support member, a shaft rotatably journaled in said stationary support member and having a cantilevered bobbin receiving portion projecting outwardly from said support member and on which the bobbin may be slid axially, said projecting portion of said shaft having an axially extending groove therein, a friction member in said groove, a spring in said groove beneath said friction member and adapted to force said friction member radially outwardly of said groove against a bobbin positioned on said cantilevered portion of said shaft, a friction brake member positioned about said shaft adjacent said support member and affixed thereto, a second shaft journaled in said stationary support member and projecting outwardly and inwardly of said support member, an annular stop member rotatably mounted on said second shaft outwardly of said support member, a thread sensing element fixed to said second shaft outwardly of said annular stop member, a spring abutment member adjustably clamped to said second shaft inwardly of said support member, spring means positioned between said stationary support member and said abutment member for rotating the feeler arm of said thread sensing element affixed to said second shaft toward said first shaft and for moving said thread sensing element against said stop member, said stop member and said thread sensing element having cooperating stepped abutment surfaces on their abutting faces adapted to hold said members in their most spaced apart positions with the feeler arm of the thread sensing element holding a bobbin engaged thereby outwardly of said friction brake member when said feeler arm is adjacent said first shaft and to permit said feeler arm to move the bobbin against said brake member when said feeler arm is rotated away from said first shaft a predetermined distance.

14. A bobbin winder mechanism comprising a rotatable driving shaft, a support for said shaft, means carried by said shaft for rotatably interconnecting a bobbin therewith when the bobbin is positioned thereon in a predetermined axial location, means carried by said support for engaging said bobbin when the latter is moved axially of said shaft in one direction from said predetermined location to terminate its rotative interconnection with said shaft, a feeler device carried by said support for linear movement in a direction parallel to the axis of said shaft and for rocking movement toward and away from said shaft and about an axis parallel to the axis of

5 said shaft, said device having an arm adapted to extend between the flanges of a bobbin mounted on said shaft and to engage the thread wound on the bobbin, spring means operatively associated with said device for rocking the same toward said shaft and for moving the same axially relative to said shaft in said one direction, and cooperating contacting means carried by said support and by said device and acting to prevent linear movement of said device and said arm by said spring means in said 10 one direction relative to said shaft until said device and said arm have been rocked a predetermined distance away from said shaft by the thread wound upon the bobbin.

15. A bobbin winder mechanism as defined in claim 14 and wherein said cooperating contacting means include 15 a part adjustably carried by said support and having a stepped surface and a part projecting from said device and engaging said stepped surface.

16. A bobbin winder mechanism as defined in claim 14 and wherein said cooperating contacting means carried by 20 said support and by said device include a part carried by said support and spaced laterally from said device.

17. A bobbin winder mechanism as defined in claim 14 and wherein said cooperating contacting means carried by 25 said support and by said device include a part rotatably adjustable on said support and having a stepped surface and a part carried by said device and engaging said stepped surface.

18. A bobbin winder mechanism as defined in claim 14 and wherein said cooperating contacting means carried by 30 said support and by said device include a part rockably adjustable on said support coaxially to said device and having a stepped surface and a part carried by said device and engaging said stepped surface.

19. A bobbin winder mechanism as defined in claim 14 and wherein the means carried by said shaft for rotatably 35 interconnecting a bobbin therewith is a friction drive means while the means carried by said support for engaging said bobbin when the latter is moved axially of said shaft in one direction is a friction brake member functioning to overcome the friction drive means between said shaft and said bobbin.
